[57] CLAIM

The ornamental design for a combined cassette tape recorder and radio, as shown and described.

DESCRIPTION

FIG. 1 is a front elevational view of a combined cassette tape recorder and radio showing my new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The patterns partially shown in FIGS. 1 and 2 are continuous within their respective areas.
